[57] CLAIM

The ornamental design for a stick-on condom holder/dispenser, as shown and described.

DESCRIPTION

FIG. 1 is a top, front, and right side perspective view of a stick-on condom holder/dispenser showing my new design;

FIG. 2 is a top, rear, and left side perspective view thereof, showing the adhesive backing strip partially removed, with the broken-line disclosure being for illustrative purposes only and forming no part of the claimed design;

FIG. 3 is a bottom plan view thereof; and, FIG. 4 is a top plan view thereof.

FIG. 3
